UNITED STATES PATENT OFFICE.

RAYMOND P. CLARK, OF ROCHESTER, NEW YORK.

DESIGN FOR A COVER FOR FRUIT-BASKETS.

46,429.

Specification for Design.

Patented Sept. 22, 1914.

Application filed March 9, 1914. Serial No. 823,587. Term of patent 14 years.

To all whom it may concern:

Be it known that I, RAYMOND P. CLARK, a citizen of the United States, residing at Rochester, in the county of Monroe and State of New York, have invented a certain new, original, and ornamental Design for Covers for Fruit-Baskets, of which the following is a specification, reference being had to the accompanying drawings, forming a part hereof.

Figure 1 is a perspective view of a cover for a fruit basket showing my new design. Fig. 2 is a plan view of this cover.

I claim:

The ornamental design for a cover for a fruit basket substantially as shown.

In testimony whereof I affix my signature in presence of two witnesses.

RAYMOND P. CLARK.

Witnesses:

ERIC ISCHINGER,
ALICE M. JOHANNS.
